UNITED STATES PATENT OFFICE

138,371

DESIGN FOR A SADDLE HORSE SWING SEAT

Charles Harvey Churchill, Cortland, N. Y.

Application February 24, 1944, Serial No. 112,689

Term of patent 14 years

(Cl. D34—15)

To all whom it may concern:

Be it known that I, Charles Harvey Churchill, a citizen of the United States, residing at Cortland, in the county of Cortland and State of New York, have invented a new, original, and ornamental Design for a Saddle Horse Swing Seat, of which the following is a specification, reference being had to the accompanying drawing, forming part thereof.

The figure is a perspective view of a saddle horse swing seat, showing my new design.

I claim:

The ornamental design for a saddle horse swing seat, as shown.

CHARLES HARVEY CHURCHILL.
